DESIGN FOR AN INTERNAL LENGTH COMPARATOR GAUGE

Walter K. Dow, Longmeadow, Mass.

Application December 10, 1946, Serial No. 135,393

Term of patent 14 years

(Cl. D52—1)

To all whom it may concern:

Be it known that I, Walter K. Dow, a citizen of the United States, residing at Longmeadow, in the county of Hampden, State of Massachusetts, have invented a new, original, and ornamental Design for Internal Length Comparator Gauge, of which the following is a specification, reference being had to the accompanying drawing, forming part thereof.

Figure 1 is a perspective view of an internal length comparator gauge showing my new design; Fig. 2 is a top plan view thereof; Fig. 3 is a front view thereof; and Fig. 4 is a rear view thereof.

I claim:

The ornamental design for an internal length comparator gauge as shown.

WALTER K. DOW.
